FIG. 5

INVENTOR.
JOHN JONES
BY
A. B. Bowman
ATTORNEY

UNITED STATES PATENT OFFICE

JOHN JONES, OF SAN DIEGO, CALIFORNIA

ELEVATOR OPERATOR POSITION-INDICATING DEVICE

Application filed October 15, 1929. Serial No. 399,751.

My invention relates to elevator position indicators, and more particularly to an indicator for the use of the elevator operator, and the objects of my invention are: first, to provide an elevator position indicator for a row of elevators which enables each operator to ascertain the position of other elevators; second, to provide an indicator for elevators, by means of which each operator may time his departure with respect to the other elevators from the upper or lower floor served by the elevators; third, to provide a position indicating means visible from the operator's seat in an elevator, by means of which the position of elevators on either side may be ascertained; fourth, to provide a positively-operated indicator of this class which can be installed without in any way disturbing the front of the elevator shafts, and fifth, to provide a device of this class which is economical of manufacture, simple of construction, and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings, and to the characters of reference thereon, which form a part of this application, in which:

Figure 1 is a diagrammatical view of a row of elevator shafts equipped with my indicating devices; Fig. 2 is a diagrammatical sectional view taken along the line 2—2 in Fig. 1, showing the position of the indicators in the shaft; Fig. 3 is a diagrammatical sectional view taken along the line 3—3 in Fig. 1; Fig. 4 is a sectional view of my indicator taken along the line 4—4 in Fig. 7; Fig. 5 is a sectional view of a double indicator; Fig. 6 is a side view in elevation of the indicating member, and Fig. 7 is an elevational view of the indicator device.

The actuating mechanism 1, cables 2, indicating members 3, curtain 4, number card 5, casings 6 and 7, and pulleys 8 form the

principal parts and portions of my novel elevator position indicating device.

Figure 1 illustrates a row of elevator shafts A, B, and C, in which operate the elevators a, b, and c, by means of the hoisting mechanism H, positioned at the upper end of the shaft, as indicated in Fig. 1, or in the pit of the shaft.

An actuating mechanism 1 is adapted to be operated by the elevator hoisting mechanism, said mechanism 1 being in the nature of a gear reduction device translating the movement of the elevators to a relatively short movement of the cable 2, which is adapted to be raised and lowered by means of said mechanism 1. The actuating mechanism 1 and cables 2 are already well known in the art, and do not form a part of this invention, except in combination with the indicating device.

At the upper floor of each elevator shaft, positioned intermediate adjacent shafts, are placed the indicators 6^a, 6^b and 7^b. The indicators face sideways with respect to the elevator shafts and are placed substantially transversely with the gap between the front of the elevator cage and the wall of the shafts.

The indicators 6^a and 6^b comprise the rectangular flat casing 6, which is provided in its one side with a lengthwise extending slot 6^c, positioned near the one edge of the casing. Opposite this slot, is placed a number card 5 on which are the spaced apart numbers 5^a, corresponding to the numbers of the floors served by the elevator. An indicating member 3, in the form of a substantially rectangular plate, is adapted to slide within the casing 6, in such a manner as to obscure one or more of said numbers 5^a, according to the position taken by said indicating member. To the bottom edge of the indicating member 3 is secured a curtain member 4 of substantially the width of the plate 3 and of a length slightly greater than the length of the slot 6^c. At the center of the upper rim of the casing 6 is provided a sleeve member 6^d through which the cable 2 is adapted to

slide, the inner end of said cable being connected to the center of the upper edge of the indicating member 3.

At the upper corner of the indicating member, exposed within the slot 6^c, is painted an arrowhead 3^a, which is adapted to draw attention to the number just above, and the position of the indicating device is so arranged that the arrowhead 3^a occupies the position in respect to the numbers, as indicated in Fig. 7, as each elevator reaches a position opposite the corresponding floor. As the plate 3 moves towards the lower end of the casing 6, the curtain folds up in the space below the lowest number.

The indicator 7^b which occupies the position between the indicators 6^a and 6^b at the upper end of the shafts A, B, and C, is of a double form, that is, it consists substantially of a pair of the indicators 6 placed back to back, having the two slots 7^e and 7^f, in which are placed similar cards 5 and over which are adapted to slide a pair of indicators 3 having curtains 4. Thus, indicator 7^b may be read from either side.

It will be noted that the operator may see the indicators through the space between the wall of the shaft and the outside of the elevator cage by looking sideways from the door of the elevator cage. Thus, when the elevator *a* occupies the upper position of the shaft A, the operator can ascertain the position of the elevators *b* and *c*, and time his departure accordingly.

In the illustration, the shafts A and B form the ends of the row of elevators, and for this reason, the indicators 6^a and 6^b are of the single-sided variety, while the central elevator shaft B is provided with the double-sided variety 7^b, which can be read from either side.

Other indicators 7^a, 7^e and 6^b are also provided at the first floor inside the elevator shafts, and for the sake of greater convenience, indicators for each elevator are shown positioned between each shaft. Thus, between the shafts A and B the indicator 6^b of the single variety and the indicator 7^e of the double variety are provided.

The indicator 6^b is operated by one branch of the cables 2^b, which passes over pulleys 8^b, while the indicator 7^e is operated by means of the cable 8^e passing over suitably positioned pulleys 2^e.

Between shafts B and C are positioned the indicators 6^b and 7^a, the former allowing the operator in elevator *a* to observe the position of the elevator *b*, while the latter enables the operators in elevators *b* and *c* to observe the position of the elevator *a*.

The indicator 6^b in this position is operated by a branch of the cable 2^b, while the indicator 7^a is operated by the cable 2^a passing over pulleys 8^a, as clearly shown in Fig. 1.

It is obvious that the height of each indicator above the floor level may be chosen to enable the best view from either direction to be obtained.

At the first floor, as at the top floor, the elevator operator is enabled to observe the positions of the other elevators by looking between the outer side of the cage and the inner side of the elevator shaft. The operators are thus enabled to remain in their respective elevator cages while awaiting their turns for departing, which they can ascertain by watching the position of the elevators indicated by the indicators 6 and 7, thus enabling the correct spacing of the elevators to be maintained.

It is obvious that the indicators may be placed at intermediate floors, if desired.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. The combination with a row of elevators, of means operable by the hoisting machinery of each elevator for indicating the position thereof, said indicating means being visible from within the other elevator cages. 100

2. The combination with a row of elevators, of position indicating means mounted within the elevator shafts intermediate adjacent elevators, and means actuating said indicating means on movement of said elevators, said indicating means being visible from within said shafts. 105

3. The combination with a row of elevators, of position indicators mounted within the shafts between adjacent elevators and visible from either side between the shaft wall and front wall of the elevator, and means operable by the hoisting machinery for actuating said indicators. 110

4. In an elevator indicator, a casing, a longitudinal slot in the one side of said casing, numerals on the inside of said casing opposite said slot, a plate slidably in said casing adapted to successively obscure said numerals, and means for moving said plate within said casing. 115

5. In an elevator indicator, a casing, a longitudinal slot in the one side of said casing, numerals on the inside of said casing opposite said slot, a narrow plate slidably mounted in said case, foldable extension means secured to the lower edge of said plate and adapted to occupy a folded position in the bottom of said casing when said plate is 130

in the lower positions and to hang over certain of said numerals when said plate occupies the higher position.

In testimony whereof, I have hereunto set
5 my hand at San Diego, California, this 27th
day of September, 1929.

JOHN JONES.
